RADIATOR FIN CONSTRUCTION

Oscar C. Palmer, Phoenix, Ariz.

Application November 27, 1931, Serial No. 577,578

3 Claims. (Cl. 257—130)

This invention relates to radiators of the type commonly employed as a portion of the water cooling system associated with an internal combustion engine, although it is to be understood that the radiator construction of the present invention is not necessarily limited to this use.

An object of the invention is to provide a radiator construction wherein each of a plurality of fins or spacing plates interposed between the water tube members of the radiator core, is of a novel design, resulting in greatly improved efficiency in conducting heat from the water tube members and disseminating the heat to the air flowing through the air cells.

15 A more detailed object is the provision of an improved spacing plate which attains its increased efficiency in conducting heat from the water tube members by an increased number of areas of contact between each spacing plate or fin and the water tube members between which it is positioned or with another spacing plate disposed between the same two tube members.

20 The invention possesses other objects and advantageous features, some of which, with those enumerated, will be set forth in the following description of the invention's particular embodiments which are illustrated in the drawing accompanying and forming a part of the specification.

25 Referring to the drawing:

Fig. 1 is a perspective view showing a portion of a radiator construction embodying the principles of the present invention.

Fig. 2 is a transverse vertical sectional view taken upon the line 2—2 of Fig. 1, with the direction of view as indicated.

Fig. 3 is a transverse vertical sectional view taken on the line 3—3 of Fig. 1, with the direction of view as indicated.

40 Fig. 4 is a view similar to Fig. 3, but showing a still further modified arrangement of spacing plates.

45 Referring first to that modification of my invention which is illustrated upon Figures 1 to 3 inclusive, I have provided an improved arrangement of fins or spacing plates 41, a group of which is placed between adjacent sets of water tube members 12, each set being arranged in one plane and parallel to the other set, whereby one 50 set of water tube members 12 of a radiator is separated from the adjacent set. Whereas the fins 41 may be employed to advantage in conjunction with water tube members 12 of various designs, the tube members 12 illustrated are each composed of a pair of vertically extending plates 13

and 14 in face-to-face abutment, each plate 13, 14 having longitudinally extending channels 16 formed therein by extruding portions of the strip from the plane of the remainder thereof. These channels extend preferably throughout the entire length of the associated plate and are placed in registry with each other, thereby forming vertically extending tubes 17 through which the water to be cooled may flow. Forming the channels 16 in this manner results in pressing portions 48 10 of the metal of each strip 13, 14 outwards from the outer face thereof, in the form of ridges or beads which project into the space or air channel 19 between the associated water tube member 12 and the water tube member next adjacent thereto. 15 A plurality of my improved fins 41 are disposed within each of the air channels 19.

The water flowing through the tubes 17 delivers heat by conduction to the plates 13 and 14 with which it is in contact, and it is the function of the fins or spacing plates 41 to conduct the greatest possible quantity of the heat thus imparted to the water tube members and disseminate the heat to the air flowing through the spaces 19 between water tube members. Each 20 25 of the fins 41 is formed from a strip of metal, preferably tinned copper, and is pressed or otherwise formed into major corrugations 43 which extend transversely of the strip, i. e., perpendicularly with respect to the beads 48.

30 Each of the crests 23 of the major corrugations 43 is indented at intervals, each indentation 24 corresponding substantially in width to the width of one of the beads 48 and the spacing between the indentations being equal to that of the beads 48, so that each indentation 24 on that face of a fin 41 which is proximal to a tube member 12 is adapted to provide a seat for one of the beads with the crest 23 of the associated major corrugation 43 extending beyond the outermost portion of that bead and engaging the water tube member 12 upon each side of the bead. The indentations 24 are provided by reversely bending the crest of each major corrugation 43 at the proper intervals, thereby providing minor corrugations 46 which extend in the opposite direction, i. e., into the valley defined by the concave side of the major corrugation, as clearly shown upon Fig. 2.

35 In order to increase the efficiency of the fins 41 in disseminating the heat accumulated thereby to the air flowing through the air cells 19, I have provided means for interrupting the smooth flow of air therethrough, and for presenting a large 40 45 number of cutting edges to the air stream. Each 50 55

end of each minor corrugation 46 is severed from the metal of the associated major corrugation 43 along both ends of the minor corrugation, the result being that each triangular air cell 22 defined by the concave side of a major corrugation 43 is divided into two smaller triangular passages 31 and 32, and a diamond-shaped passage 33, as indicated upon Figs. 2 and 3, which, however, are not continuous throughout the entire width of the fin 41, but extend for intervals, each of which corresponds in length to the width of the associated minor corrugation 46. In other words, each air cell 22 is of triangular cross sectional configuration throughout certain spaced intervals of its length, and its cross section is in the form of two smaller triangles and a diamond throughout the remaining portions of its length. Moreover, the crest 47 of each minor corrugation 46 is provided with a smaller indentation 34 which projects for a slight distance into the space or valley 35 defined by that minor corrugation. These indentations 34 extend into the air stream passing through the valley 35 and impart turbulence thereto, throwing the air across the passage and causing it to impinge with greater force against the opposite side thereof. Another advantage of providing the indentations 34 lies in the fact that when the metal of the crest 27 is reversely bent to make the indentation 34, the ends of the associated section of the minor corrugation are drawn together, thereby slightly reducing the length of the section, and assisting in drawing that section out of the hollow in the roll or die whereby the strip is being formed.

Figs. 1, 2, and 3 show one manner of grouping of the fins 41. In this modification there are two fins interposed between each two adjacent water tube members 12. The crests 47 of all the minor corrugations 46 on one side of the fin or plate 41 lie in a plane closely adjacent to and just inside the plane of the crests 44 of the major corrugations on the other side of the plate. The major corrugations 43 on one side of each plate 41 engage a water tube member 12 between the beads 48 thereof, and the crests 44 of the major corrugations of the same plate, but on the opposite side thereof, engage the corresponding crests 44 of the other plate 41 which is disposed within the same air space 19. In order to assist in holding the crests 44 which thus engage each other, against slipping laterally, I prefer that a slight depression 51 be formed in one of the crests 44 adapted to receive the crest 44 with which it is in engagement, as clearly shown upon Figs. 2 and 3.

Fig. 4 shows a still further modified form, wherein two fins 52 are disposed between each two adjacent water tube members 53, but instead of having the inner crests 54 of the major corrugations in abutment with each other, the two fins 52 are shifted slightly with respect to each other, so that the major crest 54 of one fin extends alongside a major crest of the other fin, so that the side edges of the major corrugations 56 are in face-to-face abutment throughout a portion of their width.

It is to be understood that the details of the

invention as herein disclosed, are subject to alteration within the spirit or scope of the appended claims.

I claim:

1. A radiator construction comprising a first set of water tube members, a second set of water tube members in spaced parallel relation thereto forming an air channel therebetween, each set of water tube members having beads thereon projecting into the air channel, and two fins in the air channel, each fin being a transversely corrugated section of sheet metal, the corrugations of each section forming two sets of crests, each fin having crests of one set engaging the adjacent water tube member between the beads thereon, and portions of said crests opposite the beads on the water tube member bent reversely so as to be between the crests of the other set of crests on the same fin, the crests of said other set of each fin being in engagement with each other and having portions opposite the beads reversely bent into engagement with the beads between the crests of the first set of each fin, and interlocking means holding said two fins against displacement relatively to each other.

2. A radiator construction comprising a first set of water tube members, a second set of water tube members in spaced parallel relation thereto forming an air channel therebetween, each set of water tube members having beads thereon projecting into the air channel, and two fins in the air channel, each fin being a transversely corrugated section of sheet metal, the corrugations of each fin forming two sets of major crests, one set of crests of each fin engaging the adjacent water tube member between the beads thereon, each set of major crests having portions opposite the beads reversely bent forming a set of minor corrugations between the major crests of each fin, one set of minor corrugations of each fin engaging the adjacent water tube member across the beads thereof, the other set of minor corrugations cooperating with the other set of major corrugations to embrace the sides of major crests of the adjacent fin.

3. A radiator construction comprising a first set of water tube members, a second set of water tube members in spaced parallel relation thereto forming an air channel therebetween, each set of water tube members having beads thereon projecting into the air channel, and two fins in the air channel, each fin being a transversely corrugated section of sheet metal, the corrugations of each fin forming two sets of crests, each fin having crests of one set engaging the adjacent water tube member between the beads thereon, and portions of said crests opposite the beads on the water tube member bent reversely so as to be between the crests of the other set of crests on the same fin, the crests of said other set of each fin being in engagement with each other and having portions opposite the beads reversely bent into engagement with the beads between the crests of the first set of each fin, said two fins being interlocked to hold them against displacement relatively to each other.

OSCAR C. PALMER.
